UNITED STATES PATENT OFFICE

ELLWOOD M. SHANNON, OF BALA, PENNSYLVANIA

ENGINE TRUCK

Application filed June 18, 1930. Serial No. 462,011.

One object of this invention is to provide a very flexible and easy-riding four-wheel locomotive truck with a low center plate and side frames.

5 A further object of the invention is to equalize the truck at each corner, and to provide semi-elliptic springs for cross equalizing.

In the accompanying drawings:—

Fig. 1 is a side view, partly in section, of 10 my improved locomotive truck;

Fig. 2 is a longitudinal sectional view on the line 2—2, Fig. 3;

Fig. 3 is a plan view;

15 Fig. 4 is a transverse sectional view on the line 4—4, Fig. 1;

Fig. 5 is a transverse sectional view on the line 5—5, Fig. 1;

Fig. 6 is a transverse sectional view on the line 6—6, Fig. 1;

20 Fig. 7 is a sectional plan view on the line 7—7, Fig. 2;

Fig. 8 is a perspective view of one of the fillers for the suspension links;

Fig. 9 is a longitudinal sectional view of a 25 modification of the axle box;

Fig. 10 is a sectional view on the line 10—10, Fig. 9;

Fig. 11 is a transverse sectional view of 30 another form of axle box on the line 11—11, Fig. 12; and

Fig. 12 is an end view of the axle box on the line 12—12, Fig. 11.

1 is the frame of the truck made as an integral casting and consisting of a rectangular central member having an open center, in which is located the swing bolster 2. 3

35 are the side members of the rectangular central section, connected together by transverse members 4, and a central transverse member or transom 5, which is depressed, and over which extends the bolster 2. Projecting from each corner of the rectangular central section are extensions 6, each of which consists of two arms spaced apart and connected

40 by pedestal members 7. Mounted between the pedestal sections of each extension is a journal box 9, and as shown in Figs. 1, 2 and 6 the journal boxes are tubular and extend from one side of the truck to the other, and

45 in the enlarged portions 10 are roller bear-

ings 11 of any suitable type, held against shoulders 12 by cap plates 13. The outer raceway 13b of the roller-bearings is held in place against the said shoulders 12 by the cap plate, and the inner raceway 13a is held against a flange 14 of the axle 15, on which are mounted the wheels 16. The rollers in this instance are tapered but it will be understood that other forms of roller-bearings may be used without departing from the essential features of the invention.

Extending over each end of the journal box are equalizing beams 17, which are located between the two arms of each extension. The ends of these beams are attached to links 18, which pass through spring seats 19, forming an integral part of the extensions 6, and mounted on the links below these spring seats are coil springs 20, which are carried by spring seats 21, hung from the 55 links. On the ends of the links are nuts by which the spring seats 21 and springs 20 can be adjusted. These springs take care of local shocks at the axles.

As stated above, the central transverse 75 member 5 is depressed as shown in Figs. 1, 2 and 5, and is made hollow as shown in cross-section, Fig. 2, and this member acts as a guide for the bolster 2. The bolster has a body portion 22, from which depends members 23 extending on each side of the central transverse member 5. On each side of the member 5 are wear plates 26, which are opposite wear plates 27 on the members 23. Forming an integral part of the bolster 2 80 is a center bearing 28 having a center pin opening 29 of the usual form. Mounted under each end of the body portion 22 are semi-elliptic springs 30. The ends of these springs rest on spring seats 31 carried by 85 links 32 hung from the side members 3 of the truck frame. Extending under the springs is a safety support 33, through which extend carrying bolts 34, which also pass through lugs depending from the portions 90 23 of the bolster. The ends of this safety support extend under the center of the springs and should the springs for any reason fail, then the supports carry the springs. The links 32 are spaced apart by the springs 95 100

at the lower ends and at the upper ends by fillers 35, being secured to the fillers by bolts 36. The form of the fillers is shown in Fig. 8. The two depending portions 37 of each filler are rounded at their lower ends and fit on each side of the bearing block 38, Fig. 4. The bearing blocks are secured to the frame of the truck by rivets or other suitable fastenings. This construction forms what is termed a three-point suspension type of linkage. The construction of the two-point bearings at the upper portion of the links provides a very compact and strong arrangement. The links 32 pass through slots 39 in the web 40 of the side members 3. This permits the links to swing laterally the required distance when the truck passes around a curve.

While in the main figures of the drawings I have shown journal boxes of a particular type having roller-bearings, and as shown in Fig. 6 the journal boxes enclose the shaft so that the journal boxes can be filled with lubricant, in Figs. 9 and 10 a modification is illustrated in which are independent boxes 10a for each end of the axle 15a, and in these boxes are bearings of the hexagonal type, while in Figs. 11 and 12 a floating bushing 41 is shown, which revolves in the fixed bushing 42 incorporated in the journal box 43. The bushing 41 rotates independently of the shaft 15b.

By the above construction, it will be seen that the truck frame is made as an integral casting having extensions forming the journal box support, and these journal boxes may be of any of the styles mentioned above. By using the fillers for supporting the swing links, these links may be used either in the particular truck shown or any truck having an integral or built-up frame, as there is an equalizer at each corner of the truck, and in addition two semi-elliptic springs providing cross equalizing. By making the transverse member 5, which is in fact a transom, in the manner shown, it not only guides the lateral motion of the spring bolster but also acts as a safety member in case of the breaking of the semi-elliptic springs, and it transmits to the truck the longitudinal forces of the locomotive, acting through the bolster.

I claim:

1. In combination in a truck, of a main frame made as an integral casting, and consisting of a rectangular central member having an open center, and having extensions projecting from each corner of the said center; two cross semi-elliptic springs; links suspending the springs from the side members of the rectangular center portion of the truck; a bolster supported by said springs; pedestals formed integral with the end extensions; journal boxes located in the space between the pedestals; and independent spring equalizers supporting the frame at the journal boxes.

2. The combination in a truck, of a frame made as an integral casting and consisting of a central rectangular section, open at the center and having extensions at each corner; each extension consisting of two arms spaced apart; pedestals connecting the arms and forming journal box guides; journal boxes located between the pedestals of each extension; equalizing beams resting on each journal box; links suspended from the beams; springs carried by the links and bearing against the frame; transverse semi-elliptic springs suspended from the central portion of the frame; and a bolster mounted on the semi-elliptic springs. 70 75 80

3. The combination in a truck, of an integral frame having a rectangular open central portion and axle box extensions at each corner of the frame, also made as an integral part of the frame, each axle box extension consisting of two arms spaced apart; pedestals connecting the arms and forming the bearings for journal boxes; a depressed central transverse transom; a bolster mounted above the transom and having a center bearing, and also having depending portions extending on each side of the transom; semi-elliptic springs upon which the bolster rests; and links suspending the springs from the side members of the frame of the truck. 90 95

4. The combination in a truck, of a frame having a rectangular open central member with an open center and axle box extensions at each corner of the center member; axle boxes mounted in the extensions; a depressed transom extending from one side member to the other at the center of the truck; a bolster mounted above the transom and carrying the center bearing of the truck, said bolster having depending portions extending on each side of the transom; transversely arranged semi-elliptic springs carrying the bolster; bearing blocks on the side members of the frame; slots in the frame on each side of the bearing blocks; a filler straddling each bearing block; links secured to the filler and extending through the slots in the frame; and spring supports at the lower ends of the links on which the semi-elliptic springs rest. 100 105 110

5. A spring suspension for trucks, consisting of a block arranged to be secured to the frame of the truck, said block having a raised portion at the center; a filler spanning the blocks; and links secured to each side of the filler and arranged to carry the ends of a spring. 115 120

6. The combination in a truck, of a frame made as an integral casting, and consisting of a rectangular center member having an open center and having axle box extensions at each corner; axle boxes mounted in the extensions and a local equalizing mechanism at each box; a depressed transom extending from one side member of the truck to the other and made integral therewith; a semi- 125 130

elliptic spring on each side of the transom; links suspending the springs from the side frames of the truck; a bolster carried by the springs and having depending portions extending between the springs and the transom; and a safety support carried by the depending portions of the bolster and extending under the semi-elliptic springs.
